United States Patent Office.

JACOB HARDING, OF SCHOOLCRAFT, MICHIGAN, ASSIGNOR TO HENRY I.
ALLEN & CO., OF SAME PLACE.

Letters Patent No. 79,223, dated June 23, 1868.

IMPROVED HAMES-FASTENER.

The Schedule referred to in these Letters Patent and making part of the same.

TO WHOM IT MAY CONCERN:

Be it known that I, JACOB HARDING, of Schoolcraft, in the county of Kalamazoo, and State of Michigan, have invented a new and improved Harness-Hames Fastener; and I do declare that the following is a true and exact description thereof, reference being had to the accompanying drawings, and to the letters of reference marked and making part of this specification, in which—

Figure 1 is a perspective view of my invention contracted, as in use, and

Figure 2 is the same extended, so as to receive the hames at hooks D.

The nature of my invention consists in providing the ends of the hames with metal straps, which are connected by a lever pivoted to the same, at some distance apart, the arms of the lever serving to operate the straps by drawing them nearer together, and compressing the hames firmly in their places. The lever being provided with a longitudinal projection, secures the straps in position, when contracted, by fitting into a groove prepared for it in the face of the strap, when closed, and there secured by the "spring" of the arm of the lever and strap, and holding the whole firmly in place.

Having thus explained the nature of my invention, I will now proceed to describe the construction and method of operating the same, and name its various parts.

C is a lever, hinged at its end to strap B, by the bolt 2, and to the strap A by the bolt 1. By reversing the position of the lever C, from the position shown in fig. 2 to that shown in fig. 1, the hames are drawn together and secured in position by the projection E entering the groove 3.

A is a strap, provided with two or more holes for inserting the bolt 1, to vary the length of the apparatus as required, which may be still further contracted by the strap A, by the bolt 1, through the hole 5, to the strap B, according to the space required between the hames.

What I claim as my invention, and desire to secure by Letters Patent, is—

1. The straps A and B, connected by the lever C, as and for the purposes set forth;
2. The projecting feather E and groove 3, when operated in connection with lever-arm C and strap B, substantially as described and for the purposes specified.

JACOB HARDING.
